E. F. NOELL

PRINTING PLATE CLAMPING DEVICE

Filed Jan. 26, 1925

INVENTOR:
Elmer F. Noell

BY *Acme & Allen*
ATTORNEYS.

UNITED STATES PATENT OFFICE.

ELMER F. NOELL, OF CINCINNATI, OHIO, ASSIGNOR TO THE PRINTING MACHINERY COMPANY, OF CINCINNATI, OHIO, A CORPORATION OF OHIO.

PRINTING-PLATE CLAMPING DEVICE.

Application filed January 26, 1925. Serial No. 4,743.

To all whom it may concern:

Be it known that I, ELMER F. NOELL, a citizen of the United States, and a resident of Cincinnati, in the county of Hamilton and State of Ohio, have invented 5 certain new and useful Improvements in Printing-Plate Clamping Devices, of which the following is a full, clear, and exact description, reference being had to the accompanying drawing, forming part of this 10 specification.

My invention relates to devices for retaining printing plates in place, by means of clamping jaws, adjustable in their mounting to impinge against the plate and hold it in place.

My invention is particularly designed for use in the familiar style of printing plate mounting element having a series of closely related round holes, with expanded bases.

In the production of "drop-in-hooks" which is the term applied in the art to printing plate clamping and holding pieces 25 of the type here in question, the problem has been to produce a device which has few parts, simply made, and simply operated. The devices are quite small, being on a smaller scale than the drawings in this 30 specification, which are at least twice the size of the actual devices, and the manufacture and assembly, as well as the manipulation of these small devices require close work, which is expensive unless the 35 structure is simple in the extreme.

In my structure I provide a device which has an integral jaw at one end, and a pivoted piece actuated by a screw, which rocks against the wall of the hole or groove, and 40 thus at one act thrusts the jaw against the plate, and tilts a lower end on the pivoted piece under the shoulder of the expanded base of the hole. I thus take advantage of the tilting of the jaw mounting body, but the shoulder engaging member is not on the jaw mounting piece.

There are three pieces and a pivot pin, in my device, which is obviously a simple structure to make, and a stout one in use.

50 I accomplish my objects by that certain construction and arrangement of parts to be hereinafter more specifically pointed out and claimed.

In the drawing:

Figure 1 is a top plan view showing my 55 device.

Figure 2 is a section through a mounting plate showing the device in side elevation.

Figure 3 is a perspective of the jaw 60 mounting member.

Figure 4 is a perspective of the operating member.

Figure 5 is a perspective of the screw.

Figure 6 is a perspective of the tool. 65 I have merely indicated a base block 1, in which are round holes 2, having expanded bases to form shoulder 3. The printing plate merely indicated at 4 is set on top of the base block and is to be clamped in 70 place by a series of the jaw members being brought into engagement with it, on all sides.

The pin 5 is provided of a size suitable to easily slip into the holes 2, which pin 75 has secured integrally or otherwise, but preferably permanently thereto, a cross head 6 serving as a jaw to engage the side of a printing plate.

The lower end of the body of the pin is 80 bifurcated and pivoted at 8 near its lower end is an L-shaped piece having the arm 9 and the projection 10.

The arm 9 is provided with a round bottomed groove 11, which is formed in the 85 slanting top face 12 of the arm.

The interior of the pin is provided with a threaded hole, opening out through the top of the jaw and pin as indicated at 13. In the lower portion of this hole is placed 90 a screw 14, which has a square socket in its upper end at 15 to be engaged by a tool. The tool is shown as having a head 16 and a square shank 17 to engage the screw when thrust through the hole at 13.

The device as so constructed, is adjusted with the screw upwardly in its hole, so that the L-shaped piece can be swung to a position with its arm embraced in the bifurcated legs of the pin. The projection of the L-shaped member will then pass down through the hole, and when the jaw has come into contact with the top of the plate, the lower end of the pin and the projection 10 will lie below the shoulder in the base 105 of the hole.

The jaw is then brought up against a plate, and the tool inserted to engage the screw. By turning down the screw, it will engage in the groove in the top of the arm 5, and rock it outwardly, due to the inclined relation of the groove. This will swing the top of the arm out into contact with the wall of the hole in which the device is placed, and will simultaneously move the 10 jaw tightly against the plate, and tilt the whole body of the pin so that the projection 10 is swung under the shoulder at the base of the hole. The rocking of the L-shaped piece also lifts up on the projection and 15 clamps it firmly under the shoulder of the hole.

The pin body will tilt so as to move the jaw across the hole as far as the top of the pin will go, but if the plate crosses the 20 hole intermediate its opening, the clamping action against the under shoulder will take place in the same manner, as if the pin were moved to abutment with the wall at the upper mouth of the hole.

25 I do not wish to be limited to the exact form of parts or mode of operating them, but wish to state the invention inherent in the structure described in the claims that follow.

30 Having thus described my invention, what I claim as new and desire to secure by Letters Patent, is:—

1. A printing plate clamp device, adapted for use in apertures in a base block having shoulders formed in the bottom of the apertures comprising a body having a jaw thereon, a member pivoted on the body, so as to swing into substantial alignment therewith thereby permitting insertion of the entire device in the aperture, said member 10 having a projection at the lower end thereof

for engagement with the shoulder in the base of the aperture, and means movable through the body and engaging the pivoted member to rock the same into position 45 of engagement with the wall of the hole, thereby moving the projection into position beneath said shoulder by the tilting of the body.

2. A printing plate clamp device adapted 50 for use in apertures in a base block having shoulders formed in the bottom of the apertures comprising a body having a jaw thereon, a member pivoted on the body and having an L-shape, formed so that the upward 55 portion of the L can swing into substantial alignment with the body thereby permitting insertion of the entire device in the aperture, and the angle portion of the L formed to swing beneath the shoulder, when 60 the member is rocked to force the jaw against a plate, and means in the body for engaging the said member.

3. A printing plate clamp device adapted 65 for use in apertures in a base block having shoulders formed in the bottom of the apertures comprising a body having a jaw thereon, a member pivoted on the body and having an L-shape, formed so that the upward 70 portion of the L can swing into substantial alignment with the body thereby permitting insertion of the entire device in the aperture, and the angle portion of the L formed to swing beneath the shoulder, when 75 the member is rocked to force the jaw against a plate, and means in the body for engaging the said member, said means comprising a screw, and a slanting portion at the engagement of the screw with the member, resulting in wedging it outwardly into 80 engagement with the wall of the aperture.

ELMER F. NOELL.
